United States Patent Office

Des. 200,179
Patented Jan. 26, 1965

200,179

FILING CASE

Greene C. Hosch, 529 S. E St., Lake Worth, Fla.

Filed May 14, 1963, Ser. No. 74,883

Term of patent 3½ years

(Cl. D58—11)

Fig. 2

Fig. 4

I claim:

The ornamental design for a filing case, as shown.
